(57) **CLAIM**

The ornamental design for a tape dispenser, as shown and described.

DESCRIPTION

FIG. 1 is a perspective view showing the new design for a tape dispenser;

FIG. 2 is a right side view thereof;

FIG. 3 is a left side view thereof;

FIG. 4 is a front view thereof;

FIG. 5 is a rear view thereof;

FIG. 6 is a top view thereof;

FIG. 7 is a bottom view thereof; and,

FIG. 8 is a perspective view thereof in use condition.

The broken lines in the drawing views represent unclaimed portions of a tape dispenser which are included for the purpose of illustrating unclaimed environment only, and forms no part of the claimed design. The tape shown in broken line represents unclaimed environment and forms no part of the claimed design.
